CLAIM

I claim the ornamental design for a handheld electronic device keyboard, as shown.

DESCRIPTION

FIG. 1 is a top elevation of a keyboard in accordance with the design; the broken line drawing of a device in this view is for illustrative purposes only and forms no part of the claimed design.

FIG. 2 is a left side elevation of a keyboard in accordance with the design; the broken line drawing of a device in this view is for illustrative purposes only and forms no part of the claimed design.

FIG. 3 is a front elevation of a keyboard in accordance with the design; the broken line drawing of a device in this view is for illustrative purposes only and forms no part of the claimed design; and,

FIG. 4 is a right side elevation of a keyboard in accordance with the design; the broken line drawing of a device in this view is for illustrative purposes only and forms no part of the claimed design.
